UNITED STATES PATENT OFFICE

CARL A. ANDERSON AND JESSE C. OSBORN, OF ST. JOSEPH, MICHIGAN, ASSIGNEES TO
RELIANCE ELEVATOR COMPANY, OF CHICAGO, ILLINOIS, A CORPORATION OF ILLINOIS

ELECTRIC SWITCH

Application filed March 26, 1927. Serial No. 178,722.

Cur invention relates to devices for opening and closing electrical circuits, and more particularly to such devices where the circuit is opened under load.

5 It is an object of this invention to provide a device of this character wherein the excessive sparking due to breaking the circuit is materially reduced and wherein the damage to the contacts due to such sparking is 10 substantially avoided.

Another object of our invention is to provide a circuit making and breaking device which will eliminate the uses of solid contacts such as the copper to copper or copper to 15 carbon contacts and which will also eliminate the danger of the contacts freezing or locking in closed position due to the current welding them together. Various devices have been provided in an attempt to overcome the difficulties encountered when an electrical circuit carrying a comparatively large current is 20 broken. Contacts including copper as one electrode and carbon as another or a plurality of carbon electrodes have been used, but in 25 each of these the contacts are rapidly worn away by the sparking and excessive heating when the circuit is broken. This makes it necessary to replace such contacts at frequent 30 intervals, and in the case of the copper contacts the danger of the contacts becoming so hot that they melt and run together is always present.

To eliminate these difficulties, we have provided a circuit closing device wherein conducting fluid such as mercury is utilized 35 for the electrodes or contacts and the circuit is made and broken by the contact and separation of two bodies of mercury, each of which is normally completely insulated from the other and connected to one side of the line.

40 The principal object of this invention, therefore, is to provide a circuit closing device of this character wherein the circuit is broken, not by the separation of two solid contacts or a separation of the solid contact 45 from a liquid contact, but by separating the two bodies of conducting liquid so as to eliminate all possibility of contacts freezing together.

A further object of this invention is to provide a device of this character wherein any

number of circuits may be simultaneously opened and closed with a single movement of the switch operating mechanism. This is accomplished in the present instance, by providing in a single controller drum a number of pairs of mercury contacts, each of which is entirely independent of the other in so far as electrical connection is concerned, but all of which move together as a unit.

Another object of the invention is to provide a plurality of bodies of mercury adapted to serve as electrodes within containers which are normally insulated from each other, but which by moving the mercury therein may be brought into electrical contact by causing the bodies of mercury to join each other through a port connecting the containers.

It is a further object of this invention to so construct and arrange the mercury containers and the connecting ports therebetween as to always insure that the contact between the two bodies of mercury will be made at a point which is open to the atmosphere so that upon breaking the contact any gas that may be discharged may readily escape without blowing the mercury outwardly in small particles.

In carrying out the invention, we provide a plurality of the mercury contacts within containers that are arranged in a horizontal line and carried as a unit by means of a shaft which is supported upon suitable standards whereby the mercury may be shifted from one portion to another of the container to bring the same into contact through the various ports connecting the containers.

As shown, the device is applied to a reversing switch mechanism which is adapted for reversing motors by switching the leads thereto in a manner that is well known in the art. However, the device is not limited to such use, since it is obvious that the principle may equally well be applied to devices for changing the speed of motors or to a combination reversing switch and change speed device, and in various other places where it is necessary to provide means for opening and closing the circuit which carries a large amount of current.

In the drawings:

Fig. 1 is a plan view showing the manner in which the terminals of the circuit are connected to the device;

5 Fig. 2 is a section on the line 2—2 of Fig. 1;

Fig. 3 is a sectional view on the line 3—3 of Fig. 2 illustrating the construction of the mercury containers and the position of the mercury therein;

10 Fig. 4 is a similar section showing the container shifted to bring the body of mercury in position to make contact through the port connecting it with the next container;

Fig. 5 is a section on the line 5—5 of Fig. 4 illustrating the manner in which the circuit is closed over a three-wire system; and

15 Fig. 6 is an end view illustrating means for preventing too sudden reversal of the switch mechanism.

20 Referring now in detail to the drawings, the numeral 10 represents a pair of angle irons which serve as a support for the device.

Projecting upwardly from this support are the standards 11, one of which is shown in

25 Fig. 2, which serve as a support for the drum to permit the device to rock back and forth.

This rocking action may be accomplished by hand or by any suitable power means. Any suitable stop means may be provided to limit

30 the rocking movement, as in the device shown it is only necessary that it rock through an angle of 180°.

In carrying out the invention, we provide a rotatable drum having a plurality of recessed

35 castings 12, 13, 14, 15, 16, 17 and 18, which are constructed of cast steel and may be coated with copper or other suitable material to provide a good contact surface, and these castings are separated by means of the insulating disks

40 19, 20, 21, 22, 23 and 24, which together with the recesses in the castings make up the drum and complete containers for the bodies of mercury illustrated therein.

It will be noted that the containers 15, 16

45 and 17 are in reality double containers separated by a web so as to provide two bodies of mercury between the insulating disks adjacent thereto.

The shaft shown at the right end in Figs.

50 1 and 2 and designated by the numeral 25 is a hollow shaft through which the leads of the circuit may be inserted, and these leads, which are insulated in any well known manner, as shown in Fig. 1, pass through the insulating disks and are connected to the desired containers in a manner which will be presently explained. As illustrated, there are six of

55 these leads showing a connection for a three-phase induction motor (not shown). The lead 26 is a line lead, and is connected to the container 12. The lead 27, another line lead, is connected to the container 15; and the lead 28, being the third line lead, is connected to the container 17. Going now to the load or

60 motor side, the lead 29 is connected to con-

tainer 13, lead 30 is connected to container 16, and lead 31 has a common connection to containers 14 and 18.

Now if it is desired to reverse the motor, assuming that circuit is completed between leads 26 and 29, the leads 27 and 31, and leads 28 and 30, it is only necessary to reverse the connection of two leads in order to reverse the motor. The connection just hereinbefore set forth is shown as made in Fig. 5, wherein the body of mercury as illustrated connects containers 12 and 13 so as to close circuit between conductors 26 and 29, and the mercury connects containers 15 and 14 so as to close circuit through 27 and 31, and the mercury containers 17 and 16 connect to close circuit between lines 28 and 29.

Now, if the mechanism is rotated through a half-turn so as to change the mercury from the position shown in Fig. 4, where it is in the lower recess 37 of the container, to the upper recess 38, connection will be made as before, between conductors 26 and 29 through the port 39, and connection is made between conductors 27 and 30 through the port 40, which is the reverse from the previous connection, and a third line connection is made between conductors 28 and 31 through the port 41, between containers 17 and 18. This reverses two of the leads and will effect reversal of the motor in a well known manner.

It will be noted from the level of mercury shown in Figs. 3 and 4 that even at the point of full connection the ports connecting the various containers are not submerged in mercury. This is accomplished in filling the device with mercury by testing the level by means of the testing screw 42, which is removed, so that upon filling the containers up to the level of the screw opening at 42, a constant level may be obtained in all of the containers. Limiting the level in this manner prevents the submerging of the ports between the various containers and enables any

gas which is given off to escape upwardly and outwardly through the channels 44 and 45 through a vent at 46, which, as shown, is closed by a screw, which may be entirely removed or may be slotted to provide an opening for the escaping of the gas. The path through which gas must pass in escaping will prevent the carrying of any particles of mercury therewith, and these particles will be trapped within the containers and returned to the main body of mercury upon returning the device to normal position, as shown at Fig. 3.

From the above description it will be apparent that the different bodies of mercury when the device is in the position shown in Fig. 3 are completely separated from each other by means of the insulating disks and that no contact will be made between the bodies until the device is tipped so that the mercury runs upwardly into the portions 37

or 38, depending upon the direction in which the device is tipped, and connection will then be made through the ports, the amount of mercury in contact gradually increasing until the device is tipped to the completed position, as illustrated in Fig. 4. Thus the cross-sectional area of mercury completing the contact is gradually increased from a small, thin section at first to a comparatively large section in the closed position, and upon returning the device to open position the cross-sectional area is gradually increased due to the receding of the mercury so that upon final breaking of the circuit the resistance has so increased that very little sparking occurs. The entire making and breaking of the contacts is made from mercury to mercury, and this eliminates any of the difficulties that have heretofore been encountered where contact was made between a metallic solid electrode and a mercury body, which resulted in the solid contact being gradually eaten away due to the sparking and action of the mercury when vaporized under this sparking.

To provide for means to withdraw the mercury from the device, we provide each container at the bottom thereof with an opening, as shown in Fig. 3 at 47, which is normally closed by means of a screw, but which when removed permits the mercury to drain out and in this way to be withdrawn and renewed whenever desired. However, since the mercury is substantially entirely encased and is not deteriorated to any appreciable extent by the making and breaking of the contact, it has been found to stand up for a very long period of time without any appreciable loss in quantity or without any serious deterioration. In fact, in a test of one of these devices where in five pounds of mercury was used and the circuit was made and broken ten thousand times, with the circuit carrying about sixty amperes, the loss of mercury was so small that it was difficult to measure.

In order to prevent too sudden reversal of the switch so as to throw too heavy a strain upon the motor, we provide means for stopping the rotation of the device at too great a speed from one position to the other. This means, as shown, consists of a depending finger 49 carried by a collar 50 on the end plate 51 of the device, and on the supports 10 is provided an upstanding plate 52 carrying a pivoted weight member 53 having the projections 54 and 55 thereon. These projections support the pivoted arms 56 and 57, pivoted at one end to the plate 52 in such a manner that upon movement of the finger 49 over either the arm 56 or 57, the weight 53 is moved out of normal resting position and pushes the other arm upwardly into the path of the finger 49, where it will remain until the member 53 is returned to normal position.

By this construction, if the device is rotated from one circuit closing position rapidly to

normal position and presses down one of the arms 56 or 57, the other arm will prevent its passing onward until a sufficient time lag has occurred to give the weight 53 a chance to return to normal position, and this prevents a sudden swing from one set of contacts to the other to make a sudden reversal of the motor.

The disks and containers making up the device are held together by the bolts 58, 59, 60 and 61, which pass longitudinally through the disks outside of the containers, as shown clearly in Figs. 3 and 4, and press the end plates 51 and 62 tightly against the insulating disks so that the containers are clamped rigidly therebetween.

As shown in Fig. 2, the castings are offset below the axis of rotation of the drum, when in normal position. The effect of this is to place the center of gravity of the device in such a position as to always cause the drum to return to neutral or open circuit position when the means for holding it in either extreme position is released.

This structure makes a simple contact device which will not become disarranged under service conditions and which may be readily accessible for any repairs necessary to the leads or for the withdrawal of the mercury from the containers.

While we have shown one form which our invention may take, we wish it to be distinctly understood that we do not intend to limit ourselves to the exact details shown and described, but that we intend to include as part of our invention all such modifications as come within the scope of the claims.

We have found that, in actual use of this device, the mercury contact bodies do not heat up as much as the conductors under a continuous load. This is due to the fact that when the circuit is closed the length of the mercury through which current passes is very small while the cross-sectional area is quite large in comparison. Also, the device is so constructed as to permit any hot gases given off in opening circuit to escape, and this aids in keeping the device cool. The metal castings are also good heat conductors and serve to rapidly dissipate any heat due to the current.

Having thus described our invention, what we claim and desire to secure by Letters Patent of the United States is:

1. A device of the character described comprising a plurality of plates having recesses in the side faces thereof, insulating disks separating said plates and covering said recesses, bodies of mercury in said recesses normally insulated from each other by said disks, means for connecting said bodies of mercury to electric circuits, certain of said disks being provided with ports therethrough connecting the adjacent recesses, said ports being normally spaced from the mercury in

said recesses, and means for changing the relative position of said mercury and said recesses to bring the adjacent bodies thereof into contact through said ports.

5 2. A device of the character described comprising a plurality of metallic plates having recesses in the side faces thereof, insulating disks separating said plates and covering said recesses, bodies of mercury in said recesses normally insulated from each other by said disks, terminals on said plates for connecting said bodies of mercury to electric circuits, certain of said disks being provided with ports therethrough connecting the adjacent recesses, said ports being normally spaced from the mercury in said recesses, and means for changing the relative position of said mercury and said recesses to bring the adjacent bodies thereof into contact through said ports.

10 3. A device of the character described comprising a drum mounted to rock on a horizontal axis, said drum having a plurality of transversely extending compartments therein, each compartment having one wall thereof formed of insulating material and separating it from the next adjacent compartment, said compartments being partially filled with mercury, wiring terminals carried by said drum and electrically connected to the mercury in said compartments, certain of said insulating walls having ports therethrough offset with respect to the axis of rotation of said drum and normally above the level of mercury therein, and said drum being rockable about its axis to bring the mercury in certain pairs of said compartments into engagement through said ports, the center of gravity of said drum being spaced from the axis of rotation thereof and spaced from said ports so that the drum when free will move said ports above the level of the mercury in said drum.

15 4. An electric circuit controlling device comprising a drum having a plurality of compartments therein, said compartments being partly filled with mercury, insulating means separating said compartments, said drum being adapted for connection to a suitable rocking means to shift the mercury in said compartments, said insulating means being apertured to provide means for bringing the mercury in different compartments into contact in one position of said drum, said drum having its center of gravity offset relative to its rocking axis so as to rest in a position holding the apertured portion of said insulating means above the level of mercury in said compartments upon release of said rocking means.

20 5. An electric circuit controlling device comprising a drum having a plurality of compartments therein said compartments being partly filled with mercury, insulating means separating said compartments, said drum being mounted for rocking movement to shift the mercury in said compartments, said in-

sulating means being apertured to provide means for bringing the mercury in different compartments into contact in one position of said drum, and means associated with said drum to prevent rocking of said drum above a certain speed.

25 6. A device of the character described comprising a drum pivoted about a substantially horizontal axis, a plurality of transversely extending compartments in said drum, insulating partitions between said compartments, said compartments being partly filled with mercury, one of said partitions having an aperture at one side of said axis and another of said partitions having an aperture on the opposite side of said axis, said drum having a weighted portion normally holding said drum in position to prevent contact between adjacent bodies of mercury through either of said apertures, said drum being rockable about its axis in either direction to bring mercury in the adjacent compartments into contact through said apertures.

30 7. A device of the character described comprising a drum pivoted about a substantially horizontal axis, a plurality of transversely extending compartments in said drum, insulating partitions between said compartments, said compartments being partly filled with mercury, one of said partitions having an aperture at one side of said axis and another of said partitions having an aperture on the opposite side of said axis, said drum having a weighted portion normally holding said drum in position to prevent contact between adjacent bodies of mercury through either of said apertures, said drum being rockable about its axis in either direction to bring mercury in the adjacent compartments into contact through said apertures, and means automatically operating to prevent a sudden rocking of said drum from position closing contact through one aperture to position closing contact through the other aperture.

35 In witness whereof, we hereunto subscribe our names this 7th day of March A. D. 1927.

CARL A. ANDERSON.
JESSE C. OSBORN.
